To all whom it may concern:

Be it known that I, BERNHARD M. GRAFF, a citizen of the United States, residing at the city of St. Louis, State of Missouri, have invented a certain new and original Design for a Locket, of which the following is a full, clear, and exact description, reference being had to the accompanying drawings, forming part of this specification, in which—

10 Figure 1 is a view illustrating the obverse side of my newly-designed locket. Fig. 2 is an edge elevational view of the same. Fig. 3 is a view illustrating the reverse side of my newly-designed locket.

15 This invention relates to a new and original design for lockets, the essential feature consisting of a heart-shaped locket on the obverse of which is a circular panel slightly convex, the margin of the body portion of said 20 locket being ornamented by a scroll-border, while the reverse has a margin of scrolls, the middle heart-shaped panel being raised or convex.

In the drawings, A indicates the body portion of the locket, the obverse side or face of which is provided with a circular panel a, which is slightly convex. The margin of the locket is ornamented with scrollwork, as indicated at b. The reverse face or side of the locket is also ornamented around its edges by scrollwork c, leaving raised or convex heart-shaped panel d.

What I claim is—

The design for a locket, substantially as herein shown and described.

In testimony whereof I hereunto affix my signature, in the presence of two witnesses, this 25th day of March, 1890.
